(57) **CLAIM**

The ornamental design for insulated packaging for medical specimens, as shown and described.

DESCRIPTION

FIG. 1 is a perspective view illustrating the insulated packaging for medical specimens of my design shown in a closed condition;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a perspective view of the insulated packaging for medical specimens of my design shown in an open condition;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof; and,

FIG. 15 is a perspective view of the insulated packaging for medical specimens of my design shown in an open condition with thermal regulating packs, commonly referred to as freezer packs, partially removed from interior sleeves.
